Attorney

UNITED STATES PATENT OFFICE.

ADOLPH W. HILLE, OF DENVER, COLORADO, ASSIGNOR TO AMERICAN SHALE REDUCTION COMPANY, A CORPORATION OF DELAWARE.

APPARATUS FOR SEPARATING OILS.

Application filed November 26, 1921. Serial No. 517,959.

To all whom it may concern:

Be it known that I, ADOLPH W. HILLE, a resident of the city of Denver, county of Denver, and State of Colorado, citizen of 5 the United States, have invented certain new and useful Improvements in Apparatus for Separating Oils, of which the following is a specification, reference being had to the accompanying drawings, forming a part 10 thereof.

My invention relates to centrifugal oil separators and has for its object to provide an apparatus into which crude oil or other oil consisting of or containing a mixture of 15 oils of different specific gravity and different viscosity, may be introduced and which will separate the oils delivering the light oil at one point and the heavier oils at another point, by centrifugal force.

With the above objects in view my invention consists in the apparatus hereinafter described and claimed.

Referring to the drawings:

Figure 1 is a vertical central section of an 25 apparatus embodying my invention and

Figure 2 is a detail view on an enlarged scale of the lower portion of the inner member.

In the drawings 1 indicates the vertical 30 spindle which carries the operating parts. To this spindle is secured a disk 2 supported in ball bearings 3 carried by a fixed part of the frame and near its upper end the spindle is journaled in ball bearings 3^a. 35 The spindle is thus held against downward movement and is adapted to be rotated at high speed. The spindle may be driven by any convenient means. It is here shown as provided with a worm gear 4 having its 40 teeth at such slight angle to the axis of the spindle that it may be driven by a gear 5 having suitably formed gear teeth and itself driven by any convenient power, the general construction being similar to that 45 commonly used in cream separators.

Depending from the lower end of the spindle is an outer hollow cylinder 6 closed at its lower end and having at its upper end a neck 7 within which is secured to the shaft 50 the upper end of the inner member consisting of a hollow cone 8 which extends

nearly to the bottom of the cylinder 7, and is open at its lower end. From a point 9 near its lower end, to its lower end, this inner member is cylindrical.

Near its upper end the cylinder 6, which forms the outer member of the separator, is provided with a discharge opening 10 and surrounding the outer member at this point is an annular collecting cup or chamber 11 adapted to receive the oil thrown out from the discharge opening 10, a delivery pipe 12 being provided to carry off the oil from the collecting cup.

The inner member 8 is provided near 65 its upper end with a discharge opening 13 extending through the neck 7 and an annular collecting cup or chamber 14 is provided to receive the light oil thrown out through the discharge opening 13, the collecting cup or chamber being provided with a delivery pipe 15.

Extending upward through the bottom of the outer member 6 is a delivery pipe 16 for the crude or mixed oil from which the 75 lighter oil is to be separated. This delivery pipe is provided at its upper end with a nozzle 17 so located as to deliver the oil in a relatively fine stream in line with the point 9 above which the inner member is 80 conical and below which it is cylindrical.

A guard block or bearing block 20 is arranged to receive within it the lower end of the outer member 6, the opening in this block into which the bottom of the outer 85 member extends being of such diameter that the outer member is not in contact with it at any point under normal conditions.

In operation, the spindle is driven at a speed of from 20,000 to 25,000 revolutions 90 per minute, preferably about 22,000 revolutions, giving a peripheral speed if the diameter of the outer cone is say one and one-half inches, of between one and two miles per minute, the peripheral speed of 95 the inner member, because of its smaller diameter, say one inch, being considerably less though exceeding one mile per minute. The crude oil or mixture of oils is introduced through the pipe 16 by gravity from 100 a suitable reservoir (not shown) preferably at an elevation of about three feet, and is

discharged in a fine stream or spray through the nozzle 17 against the inner surface of the inner member 8 preferably at about the level of the point 9 below which the inner member is cylindrical.

The lighter oil appears to cling to the inner surface of the walls of the inner member and is carried up these walls and, as it accumulates at the upper end of the inner member, is discharged with some force from the discharge opening 13 into the collecting cup 14. The heavier oil does not appear to adhere to the walls of the inner member but falls, carrying with it any water contained in the mixture, into the outer member 6 and is thrown outward against its walls. By reason of the greater peripheral speed of the outer member the heavier oil is caused to climb the cylindrical wall of this member and is thrown out through discharge opening 10 into collecting cup 11, though it will not climb the inwardly tapering wall of the inner member.

By reason of the differences in specific gravity and the differences in viscosity the lighter oil will cling to and climb up the inwardly tapering wall of the inner member having less peripheral speed than the outer member, while the heavier oil will not do so and requires to be forced upward, a cylindrical wall and higher peripheral speed.

The apparatus is effective to quickly separate lighter oils corresponding, in specific gravity and other characteristics, to high grade gasoline, from the crude oil produced from dry distillation of shale being particularly effective in the separation of the lighter oils from such crude oil produced by dry

distillation at a properly regulated temperature. It is also effective for the separation 40 of gasoline or other oils from water.

Having thus described my invention what I claim is:

1. A centrifugal separator comprising an outer hollow member and an inner hollow member within and carried by the outer member and of substantially less diameter and open at its lower end, the inner and outer members being each provided with discharge openings near their upper ends, means for 45 rotating the two members together, and means for directing the liquid to be treated against the inner surface of the inner member near its lower end.

2. Apparatus as claimed in claim 1 in 55 which the outer member is cylindrical and the inner member is conical.

3. Apparatus as claimed in claim 1 and in which the inner member is provided at its lower end with a downwardly extending cylindrical portion.

4. Apparatus as claimed in claim 1, in which the means for delivering the liquid to be treated comprises a nozzle adapted to deliver the liquid in a fine stream or spray, 65 against the inner surface of the inner member.

5. Apparatus as claimed in claim 1, in which the nozzle is arranged to deliver the liquid against the inner surface of the inner 70 member at the point at which its cylindrical portion joins the lower end of the conical portion.

In testimony whereof I hereunto affix my signature.

ADOLPH W. HILDE.
